(57) CLAIM

The ornamental design for equipment for the recording or reproduction of sounds or pictures, as shown and described.

DESCRIPTION

FIG. 1 is a left perspective view of equipment for the recording or reproduction of sounds or pictures showing my new design;

FIG. 2 is a right perspective view thereof;

FIG. 3 is a top perspective view thereof; and,

FIG. 4 is a bottom perspective view thereof.

The broken lines are for illustrative purposes only and form no part of the claimed design.

1 Claim, 4 Drawing Sheets

FIG. 4
